UNITED STATES PATENT OFFICE

136,862

DESIGN FOR A COMBINED PHOTOGRAPH AND CORRESPONDENCE HOLDER

Alfred Wollenberger, New York, N. Y., assignor
to Mutual Sample Card Corporation, New York,
N. Y., a corporation of New York

Application October 15, 1943, Serial No. 111,378

Term of patent 3½ years

To all whom it may concern:

Be it known that I, Alfred Wollenberger, a citizen of no country and residing in the city, county, and State of New York, have invented a new, original, and ornamental Design for a Combined Photograph and Correspondence Holder, of which the following is a specification, reference being made to the accompanying drawing, forming a part thereof.

Fig. 1 is a top plan view of the combined photograph and correspondence holder in closed position showing my new design.

Fig. 2 is a top plan view of the outside of the holder in open position thereof.

Fig. 3 is a top plan view of the inside of the holder in open position thereof and seen in slight perspective.

I claim:

The ornamental design for a combined photograph and correspondence holder, substantially as shown.

ALFRED WOLLENBERGER.
